UNITED STATES PATENT OFFICE.

GEORGE H. ARMITAGE, OF WOONSOCKET, RHODE ISLAND, ASSIGNOR TO KELLEY TICKET MACHINE COMPANY, OF NEW YORK, N. Y., A CORPORATION OF NEW YORK.

DELIVERY MECHANISM FOR VENDING-MACHINES.

1,398,994.

Specification of Letters Patent. Patented Dec. 6, 1921.

Application filed July 26, 1913. Serial No. 781,304.

To all whom it may concern:

Be it known that I, GEORGE H. ARMITAGE, a subject of the King of Great Britain, and residing in Woonsocket, county of Providence, and State of Rhode Island, have invented a new and useful Improvement, in the Delivery Mechanism for Vending-Machines, of which the following is a description:

This invention has reference to vending machines and, particularly, to machines capable of vending articles either singly or in quantities, or one, two or more consecutively, or in any number desired, and when desired, within certain limits, according to the coin or check deposited. More particularly the invention relates to feeding mechanism for coin-controlled apparatus capable of vending or delivering one, or a plurality of, articles as may be desired according to the coin deposited and, for the sake of illustration, the invention is shown as embodied in a machine which may be considered a development of the machine shown, described, and claimed in the application of Elias H. Kelley, Serial #593,339, filed Dec. 3, 1910.

Among the objects of my invention may be noted the following: to provide a circularly-moving feeding mechanism capable of delivering one or more articles, according to a predetermined rule of action imposed upon the mechanism by a coin or check deposited in the machine; to provide a feeding mechanism which when the feed drum thereof has performed its delivering function, will be locked against any further movement until its controlling mechanism is again brought into action; to provide a circularly-moving feeding mechanism which operates positively upon, and controls, the articles to be delivered, and which does not penetrate, nor in any manner deface, the articles; to provide a feeding mechanism, the path of movement of which is circular, and which is compact in form and positive in operation; to provide means by which every unit movement of the feeding drum or wheel may be registered or counted, irrespective of whether the particular movement imparted to the drum contains one or a plurality of unit movements; to provide means for adjusting or limiting the movement of the feeding wheel, according to predetermination, with reference to the value of the coin deposited in the machine; to provide, in combination with the feeding mechanism, a pull-

Specified by the inventor to be the original drawing of the invention, and to be used in conjunction with the specification, and to be referred to as the "Delivery Mechanism for Vending-Machines."

It is the purpose of the invention to provide a means by which the articles are fed for delivery, may be regulated and controlled; to provide a means by which, notwithstanding the power or force required for, or consumed in, the delivery of the articles, said power or force shall be restored to the machine at the end of each delivery operation; to provide means whereby in a cycle of movements, including delivery and preparation for delivery, the power stored in the apparatus shall be used and restored; to provide means whereby the delivery action of the machine shall be performed by one source of power; and the restoration of the power, consumed in such delivery action, shall be produced by another source of power; to provide a means by which a prime mover for the machine shall keep constantly in action a train of driving mechanism, for the purpose of periodically restoring power to a power-actuating mechanism in the machine; to provide means by which energy may be stored in the machine, controlled or adjusted as to its potential, partially consumed for a delivery action, and restored to the extent of its consumption preparatory to a subsequent delivery action; to provide a power mechanism by means of which the feeding action of the machine may be produced, and the energy of such action may be controlled and regulated; to provide a simple, cheap, positively acting, and compact feeding mechanism for vending machines capable of responding successively to the controlling action of coins of various denominations so as to deliver from the same reel, or from a single strip, and through the medium of a single drum or feeding device, one or a plurality of articles.

With the foregoing objects in view, and others which will be detailed during the course of this description, my invention consists in the parts, features, elements and mechanisms, and combinations of parts, or features, or elements or mechanisms herein-after described and claimed.

Primarily, it should be understood that since the invention in this case has reference to the delivery mechanism, and the several coöperating mechanisms and mechanical devices going to make up said delivery mechanism, the means by which the machine is tripped into action has been illustrated in the accompanying drawings only to an extent sufficient to show the mode of setting the trippers in action; also, in view of the fact that the single feed drum performs all the feeding functions in the machine in co-operation with the single strip of articles, the drawings have been curtailed so as to show but one portion of the mid-plate on which the major portion of the apparatus is secured. In the drawings:

Figure 1 is a front elevation of so much of the machine as is deemed necessary to illustrate the form and general mode of assembling the various parts of the invention;

Fig. 2 is a rear elevation of the machine shown in Fig. 1; the motor and such other parts being omitted as are deemed to be unnecessary to a proper illustration of the invention;

Fig. 3 is a top plan view of the machine as illustrated in Fig. 2;

Fig. 4 is a horizontal central section substantially on the line 4—4 of Fig. 7, looking downwardly or in the direction of the arrows;

Fig. 5 is a horizontal section substantially on the line 3—3 of Fig. 7, and looking in the direction of the arrows;

Fig. 6 is a central vertical section substantially on the line 5—5 of Fig. 7, looking toward the back of the machine, or in the direction of the arrows;

Fig. 7 is a left-side elevation of the machine as illustrated in Fig. 3;

Fig. 8 is a vertical section substantially on the line 2—2 of Fig. 3;

Fig. 9 is a vertical section substantially on the line 6—6 of Fig. 3;

Fig. 10 is a vertical section substantially on the line 1—1 of Fig. 3;

Fig. 11 is a right-side elevation of the machine as seen in Fig. 3, with the clutch exposed and the driven gear shown in outline;

Fig. 12 is a perspective showing in enlarged detail the means by which the power-spring is anchored; and

Fig. 13 is a sectional plan of a detail showing the tripper mechanism.

While I have shown in Fig. 1 of the drawings, as a motive power for the constantly running parts of the machine, an electric motor, the leads from which may be coupled to any service wires found convenient, I desire it distinctly understood that my invention is not restricted nor confined to this motive power, as any prime-mover may be employed by which to impart rotary move-

ment to the driving-shaft. Moreover, I desire it understood that my invention contemplates the use of an intermittently operating motor, or one which may be set in action when the coin is deposited in the machine, in much the same manner as such motor is operated and caused to transmit power as in the machine built according to the said application of Elias H. Kelley, above referred to. Hence, it is to be understood that, though I have shown in my present invention a constantly running motor, my invention is not confined to this mode of obtaining the primary motive power.

Referring to the drawings, and particularly to Fig. 1, the partially shown motor, has its shaft 2 provided at its lower end with a worm 3 meshing with a worm-wheel 4, carried by the driving-shaft 5, journaled in the gear-casing 6, depending from the mid-plate 7 of the machine. The mid-plate 75 may be supported in any suitable way so as to suspend or elevate the same and supported parts above the base of an inclosing casing.

The bearing and the opposite bearing for the shaft 5 are omitted from the drawings since they are unnecessary to an understanding of my invention. Whatever form the casing may have, it will be sufficient to clear the mechanism shown in Fig. 1 below the mid-plate from contact with the base of the case and permit the proper operation of the strip-controlling devices. Conveniently, the motor is mounted upon the mid-plate beside the frame of the delivery mechanism, and the latter is inclosed between, and supported by, two plates 8 and 9, shown in Figs. 1, 7 and 11, which are suitably bolted together and to the top of the mid-plate and have, in

their lower portions, extending below the mid-plate, bearings for the several shafts hereinafter described, and particularly the driven shaft 10, which, on its outer end, carries the gear-wheel 11 meshing with the smaller gear-wheel 12 on the driving-shaft. The gear-wheel 11 normally runs freely upon the hub 13 of a clutch-cam member 14, secured to the driven shaft 10 and which is coupled to a loose clutch-member 15 so as to drive the driven shaft periodically for purposes presently described. Details of the clutch are more particularly shown in Figs. 5 and 11 and comprise the three-sided or cam-member 14 secured to the driven shaft 10, three segments 16 secured to member 15, 120 and intervening balls 17, the segments surrounding the cam and the balls being located between the ends of the segments, the latter and the balls being circularly arranged about the cam and loose within the body of the gear. A spring 18, shown particularly in Fig. 1 and secured to and surrounding the hub 19 of a collar 20 secured to shaft 10, is stretched and secured to movable member 15 of the clutch, and keeps the fixed and 130

movable members in the clutch in the proper relative positions.

loose parts of the clutch apart, or in an inoperative position, in combination with arm 22, on rock-shaft 21, which engages a shoulder 23 on the periphery of the loose member 15. Another crank-arm 23 on the opposite end of the shaft is pivotally connected to a rod 24, see Fig. 10, which passes through a swiveled bearing 25 and the upper end of which is screw-threaded into a socket-portion 26, the opposite end of which is pivotally connected to a tripper-frame 27. A spring 28 surrounds the rod and is confined between a washer set upon the bearing 25, and a washer operated upon by the jam and set nuts 29 threaded upon the screw-threaded end of the rod. The tripper-frame 27 is journaled upon the shaft 30, which is mounted in bearings in the upper part of the two frame-plates 8 and 9, and is permitted slight movement upon said shaft between the adjustable stop 31 and the rock-shaft 21.

The shaft 30 also carries a segmental detent-plate 32, see Figs. 4 and 10, the hub of which is journaled upon the hub of the tripper-plate 27. The shaft also carries on the other side of the tripper-plate a pinion 33, which meshes with the segmental rack 34, on the upper end of a lever 35, journaled at 36, in the frame-plate 9, and having its lower end curved and provided with an anti-frictional roll 37, carried in a bifurcation 38, at the extreme lower end thereof. The anti-frictional roll is maintained normally in contact with the periphery of a cam 39, by means of a link 40, pivotally secured thereto at 41, and a spring 42, coiled about the stem of the link and engaging the shoulder of the link at one end and a swivel-bearing 43 at the opposite end through which the stem of the link operates, as shown in Fig. 10. The link and spring, in addition to normally holding the anti-frictional roll 37, against the periphery of the cam 39, also normally holds the segmental rack at its extreme rearward position in engagement with the pinion 33. The sleeve of the pinion 33 also has a crank-arm 44, extending therefrom, provided in its outer end with a buffer consisting of a tubular member 45, through which a pin 46 extends and in which, surrounding the pin, a coiled spring 47 is contained. The pin 46 is provided at its lower end with a head or flange 48, which engages the bottom of the tubular member and a shoulder on the upper end of the pin within the tubular member is engaged by the spring 47, the opposite end of which engages the lower end of the tubular member and thus normally maintains the pin in an outwardly projecting position with its flange 48 against the bottom of the tubular member. Pressure upon the outer end of the pin compresses the spring which acts as a cushion, as will be readily understood. The tripper-frame 27 is provided at its lower

front end with a fixed stop 49, the function of which will be presently described. The frame-plate 9 (see Fig. 11) is provided on its outer side with a plurality of lugs 50 arranged circularly and spaced apart a sufficient distance to permit the proper feeding movement, as hereinafter described, to feed a definite length of the ticket strip, according to the value of the coin deposited in the machine, or correspondingly with the tripper which is actuated through any medium desired. Each lug confines, by means of a strip 51, removably secured thereto by screws 52, the upper end of a rod 53, having near its upper end a collar 54 against which one end of a coiled-spring 55 surrounding the rod engages, the other end of the spring engaging the said strip. The lower end of the rod is connected to any suitable actuating mechanism (not shown) under coin or check control, or under control of a coin-slide, plate or other device, or of the hand of the operator, as may be desired. The upper end of each rod projecting above the confining strip on the lug engages the short arm 56 of a rocking tripper, the journal 56^a of which extends through the frame-plate 9, a similar journal 57^a being extended in alignment through the tripper plate 27, and having on its inner end a stop lug 57, having the general conformation of the letter A. The space between the legs of the lug is sufficiently extensive to permit movement of the lugs into position such as to cause its opposite ends to operate as a stop when the lug is turned for the purpose. The fixed pin 58 limits the movement of the lug 57 in opposite directions by engaging the legs thereof. See Figs. 9 and 10. The journal of the stop-lug also carries an arm 59, receiving a pin 60, in a slot thereof, said pin being carried by crank 61, carried on the tripper journal 56^a. The arm 59 has pivoted thereto one end of a link 62, the outer end of which slides through a lug 63, fixed to the tripper-frame 27. A spring 64 surrounds the link 62, and one end engages a shoulder of the link, and the opposite end engages the lug 63, the normal tendency of the spring being to force the link outwardly and thus hold the arm 59 in normal position. Extending downwardly from the arm 59 is an arm 65, the lower end of which enters an angular recess 66, in the periphery of the tripper-segment 32. The arm 65 has considerable play in the recess 66 and operates to actuate the tripper-segment a short distance in opposite directions for purposes presently described. The tripper-segment is located between the tripper-frame and the frame-plate 9; and the tripper parts 59, 60, 61, 62, 63 and 64 are located between the tripper-plate and frame-plate above the tripper-segment. The stop-lugs 57 and limiting-pins 58, however, are located on the inside of the tripper-frame above the permanent stop 49, and in sub-

stantially the same vertical plane. To the lower end of the tripper-segment is pivotally connected, at 67, a link 68, see Figs. 4 and 10, the outer end of which is journaled upon a pin 69, extending laterally from the frame-plate 9. The said pin also carries a bell-crank lever, one arm 70 of which extends into engagement with the upper surface of the link and is actuated by the latter, and the other arm 71 of which extends substantially vertically and operates as a rest for a tripping-dog of bell-crank form, the long arm 72 of which normally rests upon the vertical arm 71, and the vertical arm 73 of which is provided with a catch-head 74. A spring 75 connects the vertical arm 73 with the vertical arm 71, and normally tends to draw the two together. Hence, when the long arm 72 is lifted, the vertical arm 71 will move under the same, under the influence of the spring, and maintain the same in position to hold the feed-arm presently described. The journal of the tripping-dog carries a downwardly-extending member 76, provided with a cushion or buffer 77, of substantially the same form as that carried by the crank-arm 44. Hence, when the crank-arm is returned to initial position the engagement thereof with the buffer will depress the depending member 76, raise the long arm 72, and throw forward the catch 74, the same operation drawing the vertical arm 71 of the bell-crank forward into position to slide under the long arm 72.

Now viewing Figs. 4 and 9, it will be seen that the shaft 30 carries the sleeve 78, of a drum or closure 79, for a power-spring 80, of suitable form, one end of which is journaled to the shaft 30, see Figs. 9 and 12, and the other end of which is journaled in opposite heads of the drum. Journaled upon the sleeve of the drum is the sleeve 81, of the driving-wheel, in the horizontal flange 82 of which several flared apertures 83 are formed, the same being spaced apart suitably for driving purposes. The diameter of the driving-wheel is slightly greater than that of the drum. Mounted upon the sleeve of the driving-wheel and fixed thereto is the hub 84, of the feed-wheel 85, the periphery of which is provided with a plurality of pairs of feed-pins 86, the pairs being arranged side by side transversely of the surface of the feed-wheel and parallel with its shaft. The feed-wheel is of much greater diameter than the driving-wheel and, in consequence, a large space is provided between the two for the operation of the feed-arm. The feed-arm 87 consists of an extension of the drum 79. The arm 87 extends radially from the drum and the outer end thereof is enlarged and bifurcated. Between the arms 88, of the bifurcated enlargement, is journaled a bell-crank, one arm 89 of which projects beyond the enlargement, and is free to be engaged, as presently described, and the other arm 90 of which has the pin 91 passing through it, the lower end of which pin projects through the enlargement and is formed correspondingly to the apertures in the driving-wheel and is extended normally sufficiently far to enter in any of the apertures for the purpose of actuating said driving-wheel. Preferably, the driving-pin is confined in the enlarged member 70 so as to reciprocate therein, and is connected at its upper end to the arm 90, of the bell-crank lifting lever, which is held thereto by means of the set and jam nuts on the outer end of said driving-pin. Thus, the driving-pin may be reciprocated within the member and into and out of engagement with the driving-wheel. A coiled-spring 92, surrounding the pin 91, may be employed to hold it normally in the projected position of Fig. 9. On its outer face, the driving-arm 87 is provided with a lug 93, adapted to be engaged by the catch-head 74, of the tripping-dog, when said driving-arm is returned to its normal position, shown in Fig. 4, an extreme forward or feeding position being shown in Fig. 9.

The feeding-arm is returned to its normal position by means of the crank-arm 44, heretofore described, the buffer 46 of 95 which engages the lever-arm 89, projecting beyond the enlargement of the feeding-arm, and thus primarily lifting the feed-pin 91 from engagement with the driving-wheel and, secondarily, returning said feed-arm to 100 its normal position, shown in Fig. 4, the catch-head 74 automatically engaging the lug 93, on the face of the driving-arm, as it is returned into engagement with the buffer 77. The mode of operation of the 105 cam 39 and the segmental lever 35, through the medium of which the returning or crank-arm is operated, have been heretofore described with reference to Fig. 10; and it should be understood that the cam is of 110 such form that during a complete revolution thereof, its gradually increasing radius will operate to drive the segmental rack to the right, viewing Fig. 10, thus driving the pinion to the left and raising the returning 115 arm from its normal position, Fig. 10, to an extreme position to the left, such as to return the feeding arm to its normal or initial position under control of the latch-head 74 preparatory to again being tripped 120 into action upon the operation of the tripping mechanism under control of the coin.

The spring 80 is quite powerful and may be wound or adjusted to the proper extent by means of the arm 94, see Fig. 11, the sleeve 95 of which is keyed to the shaft 30 to which one end of the spring is secured, as heretofore described. The adjusting arm 94 is provided with a screw 96 passing therethrough and adapted to enter apertures 97 130

circularly arranged in the frame-plate 9 at a corresponding distance radially from the center of the shaft. When it is desired to set the tension or adjust the tension of the 5 spring, the screw is withdrawn while the arm is held, and then the latter is moved in a clockwise direction and the screw then again set into the aperture positioned for the required adjustment. In this simple 10 manner, the tension of the spring 80 may be adjusted so as to cause the feed-wheel, through the medium of the feed-arm, to be quickly carried to its fullest extent, or to any extent desired, according to the number 15 of articles or tickets which it is desired to have delivered from the machine, corresponding to the value of the coin deposited therein. When the feed-arm is started on its return to its initial position, as above described, the feed-pin is immediately released upon the reverse movement of the returning arm, thus permitting said feed-pin to enter an aperture in the driving-wheel, the said apertures being so spaced or distributed 20 about the periphery of the driving wheel as to provide for the accurate entrance of the feed-pin therein, irrespective of the degree of feed movement imparted to the feed wheel, and irrespective of the position of the 25 feed arm; that is to say, the feed-pin and co-operating apertures are of such form that, when the said pin is released by the returning arm, and by any accident should the pin upon the complete reverse movement of 30 the feed arm not enter an adjacent aperture, said pin will, nevertheless, rest upon the periphery of the driving wheel, and upon being released by the catch-lever, will enter the first aperture that presents itself in the 35 path of movement of said pin, the driving wheel being thus always sure to be positively engaged by the driving pin. Any reverse movement of the feed-wheel and driving-wheel is prevented by the ratchet-wheel, 40 98 which is fixed rigidly to the back of the feed-wheel, as shown in Figs. 6, 7, and 8, and which ratchet-wheel is engaged by a detent comprising the bell-crank lever 99 journaled at 100, on the inside of the frame- 45 plate 8, a spring 102 engaging the horizontal arm of said bell-crank normally forcing the vertical arm thereof into the path of movement of the ratchet teeth. Rotation of the ratchet flips the detent out of engagement with the teeth, while the spring returns the same to the position shown in Fig. 7. The normal adjustment or positioning of the detent is provided for by the screw 103, working in a lug on frame-plate 8, the 50 end of the screw engaging the journal of the detent 99, which latter is shiftable in slot 104, by releasing the clamping-nut 105. The shaft 30 also has fixed thereto a 55 sprocket-wheel 106, the same being located between the ratchet-wheel 98 and the frame- 60 plate 8, said sprocket-wheel driving a chain 107 (dotted lines) which in turn drives a sprocket-wheel 108, on the extended end of the shaft 109, of a counter or register which may be of any conventional type. It is 70 shown as located on the upper front portion of the frame of the machine in a triangular-casing 110, Figs. 1, 8, 9, 10 and 11, the front of which is provided with the usual transparency 111, through which the numerals on 75 the counting wheels may be observed. By driving the counter from the shaft 30 which carries the feeding-wheel, every movement of the feeding-wheel will be registered and the counter is so constructed as to register 80 every article delivered, whether the delivery be only one at a time, or several.

The articles carried as before described, either in reel form or stacked, are led over the guide-bar 112 of a take-up lever 113 journaled at 114, on a shaft in the lower end 85 115 of the frame-plates 8 and 9, and provided with a segmental-pinion 116 co-operating with a segmental-rack 117 journaled in the frame-plate 9. The rack has pivotally 90 connected to it the lower end of a rod 118, which passes through a swivel-bearing 119, and the upper end of which is provided with a set and jam-nut 120 and a washer, if desired. A spring 121 surrounds the rod, and 95 the upper end of said spring adjacent the swivel bearing. The normal tendency of the spring is to lift the rod and thereby the segmental rack. An antifrictional-roll 123 is carried on the journal-pin 124 which connects the rod to the rack; and the said roll is disposed in the path of movement of the cam 39 and just below the antifrictional-roll 37 carried on the lower end of the segmental-lever 35. The rotation of the cam 100 39 will depress the segmental-rack 117 against the compression of the spring 121 and thus rotate the segmental-pinion 116, so as to swing the take-up lever 113 downwardly. The upper end of the take-up lever 110 has journaled therein an antifrictional guiding spool 125. Below the same a similar spool 126 is journaled in the frame plates. The web of articles is led, as before stated, over the guide-bar 112 of the take-up lever 115 and then around the spool 126 and between the same and the spool 125 carried on the upper end of the take-up lever, and then around the latter spool and between the same and the lower grooved-end 127 of a 120 guide or retaining-plate, which lower end is secured firmly to the frame-plates in any suitable manner. The take-up lever has the two similar arms 113 between which its guiding-spool 125 is journaled, and the two 125 arms are provided at opposite sides with buffers 128 located so as to engage the journal 129 of the guide spool 126. Thus, as the take-up lever is returned to its normal position under control of the spring, the buffers 130

engage the said journal without imposing an undue blow.

The cam-shaft 10 also has fixed thereto a pinion 130 which meshes with a pinion 131 journaled in a fixed portion of the frame, such as a lug 132 projecting from the mid-plate of the machine, see Fig. 5, which latter pinion has a crank-pin 133 secured therein, which is connected by a link 134 to the pin 135 on the lug or block 136 depending from a reciprocating cutter-bar 137. The said cutter-bar slides in ways formed in a small frame 138 secured to the mid-plate of the machine, and having a forwardly extending portion 139 provided with a slot 140 which registers with a slot 141 in the cutter-bar which in turn registers with a slot 142 in the top-plate 143 of the cutter-frame. The lower surface of the top-plate of the cutter-frame has applied thereto a stationary blade 144, the same being secured in position by means of a plurality of screws 145 so that the same may be removed for sharpening when required. The cutter-bar 137 is also provided with a blade 146 secured thereto by means of screws 147 so that it may be removed for sharpening when required. By this construction it will be seen that the cutter-bar is firmly secured in the cutter-frame so as to prevent it from having any other movements than longitudinal reciprocations, and that said reciprocations are positive by reason of the driving mechanism therefor. The slots 140, 141 and 142 are at the bottom of and register with the delivery end of a chute formed by a pair of plates 148 and 149, which extend from near the upper surface of the top plate of the cutter frame to a point above the shaft of the feed wheel. The chute is rigidly fixed in position by means of supporting bars 150 extending between the two frame-plates 8 and 9, and the upper end of the chute is continued around the periphery of the feed-wheel by means of the guiding plate 151 which encircles the latter from the fixed end 127 thereof to near the upper end of the chute. The guiding-plate 151 and the periphery of the feeding wheel, form a primary chute in which the strip is confined so that it will be properly fed and maintained on the periphery of the feed-wheel in engagement with the feed-pins 86.

It will thus be seen that the tickets after being passed around the guiding and take-up spools are fed into the lower end 127 of the primary chute, and into engagement with the pins on the periphery of the feed-wheel; it being understood that the strip of tickets, or other articles to be vended, is provided with notches in its opposite edges corresponding to the position of the pins on the feed-wheel, and into which said pins enter to feed the strip around the periphery of the wheel and into the secondary-chute and down the latter through the cutting-frame in position to be

severed by the cutting blade. Delivery is made from the machine through the mid-plate, the upper surface of which is substantially flush with the lower surface of the cutting frame.

It will be noted upon reference to Figs. 9 and 10, that the first and second stops which may be designated familiarly as the five and ten cents stops,—meaning the stops at which point the feed-wheel will have received its maximum movement for the delivery of either one or two tickets respectively,—have the conventional form of the letter A, as heretofore stated. The succeeding or third stop on the extreme right of the two figures 70 would also have this form, if it were desired to deliver for a single coin three articles in a continuous strip. As herein shown, however, my invention is constructed with reference particularly to the delivery of one, two 75 and five articles for coins ranging in values as five, ten and twenty-five cents. In consequence, the third stop is modified in form so as to eliminate the extended angular portion which would operate in the path of movement of the lug on the feeding arm. In consequence, the feeding arm, when the twenty-five cent tripper is actuated, will be released in usual manner as for a five cent or a ten cent coin; but, owing to the fact that five 80 articles are to be delivered at once in a single strip, the arm must have the requisite range of movement. Such requisite range of maximum movement has been figured out to be the position of the stop 49 carried by the 85 tripper frame 27. Therefore, the feeding arm 87 passes the third stop and moves clear around until its catch lug 93, or its spring buffer 93^a, engages the stop 49; thus five 90 tickets or articles may be delivered at once, and the said stationary stop 49 operates as the corresponding element for the angular ends of the five and ten cent stops heretofore described. Conveniently, for operation in the machine, the twenty-five cent tripper 100 is arranged as shown in Figs. 10 and 11. This arrangement also gives compactness to the structure and symmetry to the arrangement of the tripper rods and the actuating mechanism therefor.

As heretofore explained, the spring 80 is very powerful and is compelled to do considerable work and is, in consequence, subjected to a great deal of vibration, tending to produce crystallization, which tends to 105 make the spring snap or break at the point of juncture with the anchoring means therefor, both on the drum and on the shaft. To overcome this, a construction has been provided by means of which the vibration 110 at the points indicated have been eliminated. This construction is shown in Fig. 12, wherein the parts are shown very much enlarged, and the shaft 30 is shown as provided with a groove 152 with oppositely 115

extending recesses 153, and which groove gradually decreases in depth until it merges flush with the surface of the said shaft 30. Thus the winding of the spring about the 5 shaft to which it is anchored is gradual from the surface thereof to its point of anchorage, see Fig. 9, so that no bends or angles are produced in the said spring. The 10 spring 80 is anchored by means of an attached clamp or holder 154 between the parts of which the spring is held by means of rivets 155, the said holder having at its free end a laterally extended journal pin 156, the ends of which, beyond the edge of the 15 spring, extend into the recesses 153. Thus, the spring is anchored by a freely moving journal pin to the winding shaft 30. The same means for anchoring the other end of the spring may be provided excepting that 20 the extensions of the journal pin, indicated in Fig. 9 as 157, will enter apertures in the opposite heads of the drum housing the spring. By this mode of anchoring the spring, the latter is also held from slipping 25 laterally on its shaft 30, since the walls of the groove 152 will confine the same, as will be readily understood with reference to Fig. 12, and the opposite plates 79 will perform a similar function for the opposite end of 30 the spring.

Having thus described the details of my invention, the following brief statement of the mode of operation of the machine will be readily understood:

35 Bearing in mind that the spring 80 is wound up or set so as to have sufficient power to drive the feeding-arm and the feeding-wheel far enough to deliver the maximum number of articles, and also bearing 40 in mind that the motor 1, in this form of my invention, is constantly running and driving the shaft 5 and, consequently, the gears 12 and 11, the latter running freely upon the single revolution shaft 10, it will be understood that when a coin is placed in the slot, or in the slide, or other receptacle provided in the machine for it, one or the other of the tripping-rods 53 will be pushed longitudinally vertically so as to actuate the 45 tripper arm 56. Thus, the tripping mechanism shown in Figs. 9, 10 and 13 will be set in action and the toggle between the link or rod 62 and the arm 59 will be depressed or moved from the extreme position shown 50 in Fig. 10 to an opposite extreme position on the other side of a straight line extending from end to end of the toggle parts and passing through the centers thereof. This operation will cause the stop 57 which is 55 being manipulated, if, in applicant's machine, it be a five or ten cent coin, to extend its end downwardly in the path of movement of the feed-arm or the catch-plate and buffer 93—93^a thereof. The same movement that 60 65 throws the angular end of the stop into

stopping position will actuate the arm 65 so as to give slight movement to the segment 32, in a clockwise direction, Fig. 9, which will result in lifting the link 68 and the arm 70 and moving the arm 71 rearwardly. This 70 action will release the arm 72 of the catch-lever resulting in drawing the catch-head 74 rearwardly under control of the spring 75, which immediately frees the catch-plate 73 of the feed-arm. The feed-pin being de- 75 pressed under spring control so that its conical end is entered in an aperture in the drum 82, will now, under the power of the spring 80, move with its feed-arm circularly, or in the general direction of the stop 49, 80 until it engages the stop 57, which is interposed in its path. Since said stop 57 is carried by the tripper-plate 27, the jar imposed upon the latter by engagement of the feed arm with the tripper-stop, will give the same 85 a slight circular movement around the shaft 30. The feed arm has, by the movement just described, fed the strip of tickets or articles the required distance through the medium of the feed wheel, the pins of which 90 engage said strip so that the requisite length has been fed past the cutting blades through the several apertures as heretofore explained. In consequence, the strip is ready to be severed by the cutting-blade 146. The 95 slight movement imparted to the tripper-plate 27, as just described, depresses the rod 26—24, thus rocking the shaft 21 and depressing the arm 22 releasing, in consequence, the member 15 of the single revolution clutch. The said member, therefore, is moved upon the shaft 10 sufficiently to cause the segments 16 thereof to push the balls 17 circularly about the cam member 14 fixed upon the shaft 10. The balls, in 100 consequence, are moved radially relatively to the shafting 10 which causes them to frictionally engage or bind between the cam surfaces of the member 14 and the inner periphery of the gear-wheel 11, or a steel or hardened lining applied thereto. In this manner, the gear 11 is fixed for movement with the shaft 10, so that under the influence of the gear 12, said gear 11 will drive the shaft 105 110 for a single revolution, or until the stop 115 shoulder 23 of the member 15 is brought into engagement with the arm 22, which, immediately upon releasing the said member 15, returns to normal or upper position under the influence of the spring 28, surrounding 120 the rod 24, this action likewise returning the tripper-plate 27 to its normal position substantially in engagement with the stop 31. Thus, a single revolution is also given to the cam 39 in the direction of the arrow, 125 shown in Fig. 10. The gradually increasing surface of the cam 39 moves the lower end of the segmental lever 35 to the left and the rack 34 carried thereby to the right, thus rotating the pinion 33 in a clockwise direc- 130

tion and moving the returning arm 44 vertically so as to cause the extension 44^a thereof to engage the depending arm 89 of the lever which controls the action of the driving pin 91. Immediately upon engagement with the extension 44^a with said lever-arm 89, the feed pin is lifted from engagement with the flange of the driving wheel so that the feeding-arm 87 may be returned by the returning arm 44 to initial position, shown in Fig. 4, the returning arm carrying the feeding arm back until the tripper-plate 93 engages the buffer 77, whereupon the bell-crank catch-lever will be depressed or swung about its pivot so as to present the catch head 74 in position to engage the catch-plate 93 and prevent the feed arm from being returned under influence of the spring 80. The returning movement of the feeding arm is accomplished during substantially a half revolution of the shaft 10 and cam 39, and during the other half revolution thereof, the segmental lever returns the returning arm to its normal or depressed position, shown in Fig. 9, the antifrictional roll 37 of the segmental lever dropping into the depression of the cam as the latter presents itself to said roll. It will be understood, of course, that as the latch-head 74 is moved forwardly or to the right, Fig. 9, the arm 72 is lifted, the segment 32 is returned to normal position, the arm 70 is depressed, the arm 71 is moved to the right, Fig. 10, and slides under the arm 72, thus holding the catch-head so as to hold the feeding arm. During the movements just described, the cam 39 is also operating upon the anti-frictional roll of the rack-segment 117, causing the latter to actuate the pinion 116 to depress the pull-off or take-up lever 113, to draw a sufficient amount of the strip from the stack or reel from which it is fed. By so doing the pull-off or take-up arm relieves the feeding mechanism of any undue strain or retarding movement which might occur were such device not employed. Likewise, the strip is held by the rolls 125 and 126, the guide 112, and the grooved portion 127 of the primary-chute in position so as to be freely drawn through the primary chute by the feeding-wheel. Of course, as the power shaft 30 is moved, the sprocket-wheel 106 thereof actuates the chain 107 to drive the sprocket-wheel 108 on counter-shaft 109, which gives the requisite movement to the counting wheels of the counter 110. Thus, the movement of the shaft for any number of articles to be delivered will be registered at the counter, and this will be in accordance with the value of the coin and the number of articles delivered from the machine. As the shaft 110 rotates, the pinion 130 likewise rotates in the direction of the arrow, Fig. 8, which drives the pinion 131 in opposite direction, or clockwise, thus reciprocating the link 134, the cutter-bar 137 and the cutter-blade 146 carried thereby. This action causes the cutter-blade 146 to shear off the article, or requisite length of the strip, and return to its normal position, shown in Fig. 8. It will thus be seen that after the coin has been deposited in the machine, the operation of the latter is entirely automatic from the normal cocked and ready-for-action position of the machine until all the parts have gone through their functional movements and been returned to said position again. In other words, the insertion of the coin in the machine trips the proper tripper into action, which uncocks and sets off the machine, which automatically goes through the various actions described and all the parts of which are returned to normal or cocked position again, ready for a repetition of the said functional movements. Hence, the machine is always ready for action and has its power stored therein for carrying out its rule of action in its various branches.

Having thus described my invention, what I claim and desire to secure by Letters Patent is:

1. A vending apparatus having, in combination, means for delivering articles therefrom; means by which the delivery means may be set in action; a motor; a single revolution clutch; means connecting the motor with the single revolution clutch for actuating the latter; and connecting means between the single revolution clutch and the delivery means whereby to reset the latter for a successive operation.
2. A vending machine having, in combination, a constantly running motor; a power device; means for delivering articles from the machine; connections between the power device and the delivery means for actuating the latter; and connections between the constantly moving motor and the actuating means for resetting the latter for a successive operation.
3. A vending machine having, in combination, a driving motor; a power device; means connecting the power device with the delivery means for actuating the latter; connections between the actuating means and the driving motor; including a single revolution clutch for driving said actuating means; and means for tripping the single revolution clutch into action to permit the driving motor to perform its function in the machine.
4. A vending machine having, in combination, a power device; means for delivering articles from the machine; means for normally holding the delivery means under control; means for tripping the delivery means into action; and positively actuated means for resetting the delivery means for a successive operation.
5. A vending machine having, in combi-

1. A vending machine having, in combination, means for feeding articles in a continuous strip to delivery position; a tripping device for controlling the operation of the feeding means; means for severing the articles from said strip at the delivery position; and a controlling means for the strip, set in operation by the tripping device, acting to supply the same to the feeding means to prevent undue strain upon the strip during the succeeding feeding operation.

2. A vending machine having, in combination, means for delivering different quantities of articles therefrom including a rotary article feeding drum; a plurality of tripping devices for controlling the operations of the delivery means; and means whereby one or the other of said tripping devices may be brought into action so as to control the amount the machine will deliver.

3. A vending machine having, in combination, means for delivering articles therefrom; means for periodically actuating the delivery means; a single revolution shaft; means for actuating the latter; a cutter and connections between the cutter and single revolution shaft for actuating the cutter immediately after each delivery action.

4. A vending machine having, in combination, means for feeding articles in variable quantity from a continuous strip to delivery position; a cutter for detaching a predetermined number of articles from the strip at the delivery position; means acting upon the strip for controlling the slack thereof; and mechanical means for actuating the delivery means, the cutter, and the controlling means.

5. A vending machine having, in combination, means for delivering articles therefrom, comprising a feed wheel having means for engaging the articles to be delivered; a feeding arm for driving the feed wheel; controlling means for regulating the extent of movement of the feeding arm; and means for returning the feeding arm to normal position after each feeding action thereof.

6. A vending machine having, in combination, means for delivering articles therefrom, comprising a feed wheel having means for engaging the articles to be delivered; a feeding arm for driving the feed wheel; controlling means for regulating the extent of movement of the feeding arm; means for returning the feeding arm to normal position after each feeding action thereof; a cutter; and means for actuating the same during the operation of the returning means.

7. A vending machine having, in combination, means for delivering articles therefrom, comprising a feed wheel having means for engaging the articles to be delivered; a feeding arm for driving the feed wheel; controlling means for regulating the extent of movement of the feeding arm; means for returning the feeding arm to normal position

after each feeding action thereof; means for controlling the slack of the strip to be fed; and means for actuating the latter during the operation of the returning means.

8. A vending machine having, in combination, a feeding wheel; a power device for actuating the same, located within the circumference of said wheel; a driving arm connected to the power device; and connections between the driving arm and the feed wheel for actuating the latter, including a yielding pin; and means for returning the arm to normal position after the power device has actuated the same for a predetermined delivery.

9. A vending machine having, in combination, means for delivering articles therefrom, comprising a feed wheel; a driving arm therefor; a power device for actuating said arm; connections between the driving arm and the feed wheel; a plurality of tripping devices; means for holding the driving arm in a normal position; connections between said holding means and the tripping devices, whereby the driving arm may be released from the holding means; and means for returning the driving arm to normal position in engagement with the holding means.

10. A vending machine having, in combination, means for delivering articles therefrom; a plurality of controllers for regulating the delivery of the articles; and a single train of mechanism between the controllers and the delivery means for tripping the latter into action, when any one controller is operated.

11. A vending machine having, in combination, means for delivering articles therefrom, including a circularly moving driving arm; a plurality of controllers for regulating the action of said arm; a single train of mechanism between the controllers and the driving arm for tripping the latter into action; and means for returning the driving arm to position so that the controllers may assume control thereof after a tripping action.

12. A vending machine having, in combination, means for delivering articles therefrom, comprising a feed wheel; a driving arm therefor; connections between said arm and said wheel for actuating the latter; a power device for actuating the arm; and means for regulating the action of the power device upon said driving arm.

13. A vending machine having, in combination, means for delivering articles therefrom, comprising a feed wheel and a connected driving wheel; a driving arm and spring-controlled means between the driving wheel and arm; means for actuating the driving arm to drive the feed wheel; and means for returning the driving arm to normal position after a feeding operation, and

- simultaneously breaking the connection between the same and the driving wheel.
18. A vending machine having, in combination, means for delivering articles therefrom, including a feed wheel; a driving arm therefor; connections between the feed wheel and the driving arm for actuating said wheel; means acting upon the arm constantly tending to propel the latter; means for holding the arm in a normal position; and means for releasing the arm to permit the propelling means to assume control thereof.
19. A vending machine having, in combination, a mid-plate; a pair of supporting plates mounted in parallelism thereon and extending above and below the same; a delivery mechanism mounted upon the supporting plates above the mid-plate; a slack controller mounted upon the supporting plate below the mid-plate; a cutter mounted upon the mid-plate; a chute mounted upon the supporting plates, and connecting the delivery mechanism with the cutting means; and means for actuating the several means and mechanisms.
20. A vending machine having, in combination, means for delivering articles from a continuous strip; means for cutting a predetermined number of articles from said strip; a power device for intermittently actuating the delivery means; a slack controller for the strip; a single revolution device for actuating the controller and the cutter; a constantly running motor; connections between the motor and the cutter and controller, whereby the latter may be actuated; a tripper mechanism and connections between the latter and the power device; and connections between the tripper mechanism and the single revolution device, whereby when the tripper is actuated the power device will be brought into action for actuating the delivery mechanism; and the single revolution device will be operated to actuate the cutter and the controller through the medium of the constantly running motor.
21. A vending machine having, in combination, feeding means including a driving part, a power spring having clamping means at the end thereof for anchoring the same to the driving part including a journal pin; and a groove in the driving part of gradually decreasing depth for receiving said clamp, said groove having oppositely extending recesses for receiving said pin.
22. A vending machine having, in combination, feeding mechanism; means for actuating the feeding mechanism including a power spring and means for loosely anchoring the end of said spring for the purpose of preventing crystallization of the material of the spring.
23. A vending apparatus comprising means for delivering articles therefrom, 65 said means including a movable element normally in position to begin delivery as soon as said element is set in motion, means for actuating said element in varying degrees, and means for returning said element to starting position when each delivery is ended.
24. A vending machine comprising delivery means, said means including an element movable with respect to an axis, normally in position to begin delivery as soon as said element is set in motion, means for actuating said element in varying degrees, and means for returning said element to starting position when each delivery is 70 ended.
25. A vending machine comprising means for delivering articles therefrom; said delivery means including a movable element to effect delivery, means for returning said element to starting position when each delivery is 75 ended, and means actuated by said element to release said returning means for operation.
26. A vending machine comprising means 80 for delivering articles therefrom, said means including a movable element to effect delivery, means for severing one or more of said articles and returning said element to starting position when each delivery is 85 ended, and means actuated by said element to release said last named means for operation.
27. A vending machine comprising means 90 for delivering articles therefrom, said means including a movable element to effect delivery, means for actuating said element in varying degrees, means for returning said element to starting position at the end of each delivery, and means actuated by said 95 element to release said last named means for operation.
28. A vending machine comprising means 100 for delivering articles therefrom, said means including a movable element to effect delivery, means for actuating said element in varying degrees, means for detaching one or more articles and returning said element to starting position when each delivery is 105 ended, and means actuated by said element to release said last named means for operation.
29. A vending machine having, in combination, means for delivering articles therefrom, including a feeding device for engaging the articles to be delivered; a feed arm for driving the feeding device; controlling means for regulating the extent of movement of the feed arm; and means for returning the feed arm to starting position 110 after each feeding action thereof.
30. A vending machine having, in combination, means for delivering articles there-

- from, including a feeding device; a driving arm therefor; connections between the feeding device and the driving arm for actuating the feeding device; means acting upon the arm constantly tending to propel the latter; means for holding the arm in a normal position; and means for releasing the arm to permit the propelling means to assume control thereof.
31. A vending machine having, in combination, means for delivering articles therefrom, including a movable element normally in position to begin a delivering operation; means for driving said element to a predetermined degree for a delivering operation; and means for driving said element a further predetermined degree to restore the same to normal position.
32. A vending machine having, in combination, means for delivering articles therefrom; including a movable element normally in position to begin delivering operations; means for actuating said element for a delivering operation; means for variably checking the travel of said element; and means for additionally actuating said element to restore the same to normal position.
33. A vending machine having, in combination, means for supporting, guiding and delivering tickets or similar articles from a single strip, including a rotary drum and means for actuating said drum variable distances according to the number of tickets it is desired to have the machine deliver.
34. A vending machine having, in combination, means for supporting, guiding and delivering articles therefrom, including a rotary member normally held from rotation; means for actuating said member variable distances and means cooperating with the holding means for tripping the same into action to enable the said actuating means to cause the rotary means to make a delivery according to predetermination.
35. A vending machine having, in combination, means for guiding and delivering articles from a single strip, including a rotary drum, means on the drum for cooperating with the strip, and means for variably driving the drum so as to deliver as many articles as may be required.
36. A vending machine having, in combination, means for feeding articles in a continuous strip to delivery position; means for severing articles from said strip at the delivery position; a controlling means for the strip, acting to supply the same to the feeding means including means for taking up slack in the strip.
37. A vending machine having, in combination, means for delivering articles from a continuous strip including a rotary member; means for moving said rotary member variable distances so as to deliver any desired number of articles; and means for severing the desired number of articles after the delivery operation.
38. A vending machine having, in combination, means for delivering different quantities of articles therefrom, including a rotary drum; a plurality of tripping devices for controlling the operations of the delivery means; and means whereby one or the other of the tripping devices may be brought into action so as to control the amount of rotation imparted to the drum.
39. A vending machine having, in combination, means for delivering articles therefrom, comprising a circularly moving member; driving means therefor; connections between said driving means and member for actuating the latter; a power device for actuating the driving means; and means for regulating the action of the power device upon the driving means.
40. A vending machine having, in combination, means for delivering articles, comprising a movable member normally in position to begin a delivery operation; means for returning said member to starting position after the completion of a delivery operation; a power device; and connections from said device to said member for producing the delivery operation.
41. A vending machine having, in combination, means for delivering articles, comprising a movable member normally in position to begin a delivery operation; means for controlling the extent to which said member may move for a delivery operation; means for returning said member to starting position after the completion of a delivery operation; a power device; and connections from said device to said member for producing the delivery operation.
42. A vending machine having means for delivering articles, comprising a uni-directionally movable element and a member normally in position to begin a delivery operation; means for controlling the extent to which said element and member may move for a delivery operation; means for returning said member to starting position after the completion of a delivery operation; a power device; and connections from said device to said member for producing the delivery operation.
43. A machine of the character described, having an exit for tickets from a strip, comprising, in combination, a rotatable drum provided with means adapted to engage the ticket strip for feeding the same through the exit; a knife for severing the issued tickets from the strip; means for actuating the knife; means for rotating the drum variable distances and adapted to set the knife actuating means in operation; and means for returning the knife to its normal position.
44. In a machine of the character described having an exit for tickets from a rolled

ticket strip, the combination of a rotatable drum; a support whereon the ticket roll is mounted; pins borne by the drum and adapted to coöperate with the ticket strip to thereby feed the same through the exit; means for rotating said drum; a member having a revolute roller for engaging the ticket strip; means for holding the roller in engagement with the ticket strip between the roll and the drum; to thereby hold said strip taut; and means for holding the ticket strip in engagement with the said roller.

45. In a machine of the character described, the combination of a shaft; means for limiting the forward movement of the shaft; and shiftable means for actuating the limiting means.

46. In a machine of the character described, the combination of a shaft; means for limiting the forward movement of said shaft; shiftable means for actuating said limiting means; and means for preventing retrograde movement of the shaft until the same reaches the limit of its forward movement.

47. In a machine of the character described, the combination of a shaft; means for limiting the forward movement of said shaft; shiftable means for actuating said limiting means; means for preventing retrograde movement of the shaft until the same reaches the limit of its forward movement; and means for preventing the forward movement of the shaft until the same returns to its initial position.

48. In a machine of the character described, the combination of a shaft; means for moving the shaft forward variable distances; and shiftable means for actuating the shaft-moving means.

49. In a machine of the character described, the combination of a shaft; means for variably limiting the forward movement of said shaft; and shiftable means for actuating said limiting means.

50. In a machine of the character described, the combination of a shaft; means for rotating the same forward and backward; tripping means; and means actuated by the tripping means for limiting the forward movement of the shaft.

51. In a machine of the character described, the combination of a shaft; means for rotating the same forward and backward; a plurality of tripping means; and instrumentalities actuated by said tripping means for limiting the forward movement of said shaft.

52. In a machine of the character described, the combination of a shaft; a rotatable drum supported thereby; means for actuating the drum variable distances; a plurality of devices for limiting the distance to which the drum may move; and each of said devices being provided with a projec-

tion located in the path of travel of the drum-actuating means.

53. In a machine of the character described, the combination of a shaft; a drum carried thereby; means for actuating the drum; a plurality of means interposed in the path of travel of the actuating means to limit its movement; and means coöperating with the limiting means for controlling the position thereof so as to determine the extent of travel of the actuating means.

54. In a machine of the character described, the combination of a shaft; a drum carried thereby; means for actuating the drum; a plurality of means interposed in the path of travel of the actuating means to limit its movement; means coöperating with the limiting means for controlling the position thereof so as to determine the extent of travel of the actuating means; and means for returning the actuating means to initial position.

55. In a machine of the character described, the combination of a rotary drum; of means for actuating the said drum; means for normally locking the actuating means for action; means operating in the path of travel of the actuating means to limit its forward movement; and means for tripping the limiting means into operative position.

56. In a machine of the character described, the combination of a rotary drum; means for actuating the same; means for normally locking the actuating means from action; a plurality of means arranged in co-operative relation to the actuating means for limiting the movement of the latter; means coöperating with the limiting means for tripping the same into action to co-operate with the actuating means; and means for setting the actuating means in operation.

57. In a machine of the character described, the combination of a rotary drum; means for actuating the same; means for normally locking the actuating means from action; a plurality of means arranged in co-operative relation to the actuating means for limiting the movement of the latter; means coöperating with the limiting means for tripping the same into action to co-operate with the actuating means; means for setting the actuating means in operation; and means for returning the actuating means to normal position.

58. A machine of the character described having an exit for tickets from a ticket strip and comprising, in combination, a shaft; a drum revoluble on said shaft and having means for feeding the strip through the exit; means revolvably mounted on said shaft for intermittently rotating the drum; a knife for severing tickets from the strip; means for actuating the knife to perform its

functions; and means co-operatively arranged for causing the knife to perform its functions at the end of a feeding operation.

59. A machine of the character described having an exit for tickets from a ticket strip and comprising, in combination, a shaft; a drum mounted upon said shaft for rotation and having means for feeding the ticket strip through the exit; rotary means for driving the drum intermittently; severing means co-operatively arranged relatively to the drum-driving means, and adapted to be set in operation when the latter is operated; and means for returning the knife and drum-15 driving means to normal position.

60. A machine of the character described having an exit for tickets from a ticket strip and comprising, in combination, a rotatable drum provided with means adapted to engage said ticket strip for feeding the same through the exit; a knife for severing the issued tickets from the strip in the machine; means for rotating said drum and adapted to start said knife in operation; means for 25 returning said knife to its normal position; and means for preventing the knife from operating until the drum has been set in operation.

61. In a ticket dispensing machine, the combination of a ticket delivering drum; an oscillating device adapted when moved in one direction to connect with and propel the drum; means for disengaging the device from the drum after the completion of its travel in the direction in which it moves when propelling the drum; a cutter; and means actuated by the oscillating device for causing the cutter to perform its functions.

62. In a ticket dispensing machine, the combination of a ticket delivering drum; an oscillating device adapted when moving in one direction to connect with and propel the drum; means for disengaging the device from the drum at a predetermined time; a cutter; and means for actuating the cutter to perform its function.

63. In a ticket dispensing machine, the combination of a ticket delivering drum; an oscillating device adapted when moving in one direction to connect with and propel the drum; means for disengaging the device from the drum at a predetermined time; means for returning the device to original position; a cutter; and means for actuating the latter to cause the same to perform its functions.

64. In a ticket dispensing machine, the combination of a ticket delivering drum; an oscillating device adapted when moving in one direction to connect with and propel the drum; means for variably limiting the travel of said device; means for disengaging the device from the drum at a predetermined time relatively to its limit of travel; and a

cutter and means for actuating the same to perform its functions.

65. A ticket-issuing machine provided with a ticket-issuing mechanism that is normally set in condition to operate automatically whenever it is released, a locking means for said mechanism which prevents it from operating, means governed by the operator for controlling the issuance of one or a plurality of tickets, and means for automatically tripping said locking means so as to permit said issuing mechanism to act whenever said controlling means is actuated.

66. A ticket-issuing machine provided with a device for feeding a ticket-strip and with a device for severing said strip, an operating mechanism for imparting movement to said devices; means for storing up energy in said operating mechanism and holding it in readiness to act, a controlling mechanism which determines the number of tickets that are issued at each cycle of operations, and means for causing said operating mechanism to act automatically whenever said controlling mechanism is actuated.

67. A ticket-issuing machine provided with a controlling mechanism for determining the number of tickets that are issued at each cycle of operations of the machine, a ticket-issuing device, a spring-actuated operating mechanism for said device, means for storing up energy in said operating mechanism when the machine is in motion and holding it in condition to act, and means whereby said operating mechanism imparts movement to said ticket-issuing device after said controlling mechanism has been actuated.

68. A ticket-issuing machine provided with mechanism under control of the operator for controlling the issuance of one or a plurality of tickets, a ticket-issuing mechanism, resilient means for causing said ticket-issuing mechanism to operate, a motor-driven element for storing up energy in said resilient means so that it will be ready to operate at the next cycle of operations of the machine, means for holding said resilient means under tension, and means governed by said controlling mechanism for determining when said issuing mechanism shall act.

69. A ticket-issuing machine provided with mechanism under control of the operator for issuing one or a plurality of tickets, resilient means forming part of said ticket-issuing mechanism, a motor driven element for storing up energy in said resilient means, means for automatically locking said mechanism after said resilient means has been placed under tension, and means controlled by the operator for releasing said locking means.

70. A ticket-issuing machine provided with mechanism under control of the operator

- for issuing one or a plurality of tickets, resilient means forming part of said ticket-issuing mechanism, a motor-driven element for storing up energy in said resilient means, means for automatically locking said mechanism after said resilient means has been placed under tension, spaced devices for limiting the degree of movement of said ticket-issuing mechanism, and means controlled by the operator for releasing said mechanism from said locking means and for setting up one of said spaced devices. 55
71. A ticket-issuing machine provided with a ticket strip feeding mechanism and with a cutting mechanism for severing said strip, a spring for moving said feeding mechanism forwardly, a motor-driven element for positively storing up energy in said spring and for actuating said cutting mechanism to sever the ticket strip and a controlling mechanism for determining the number of tickets that are issued at each cycle of operations and for causing said feeding mechanism to operate automatically. 60
72. A ticket-issuing machine provided with a device for feeding a ticket-strip and with a device for severing said strip, an operating mechanism for imparting movement to said devices, means for storing up energy in said operating mechanism and holding it in readiness to act, a controlling mechanism which determines the number of tickets that are issued at each cycle of operations, and means for causing said operating mechanism to act automatically whenever said controlling mechanism is actuated. 65
73. A ticket-issuing machine provided with a controlling mechanism for determining the number of tickets that are issued at each cycle of operations of the machine, a ticket-issuing device, a spring-actuated operating mechanism for said device, means for storing up energy in said operating mechanism when the machine is in motion and holding it in condition to act, and means whereby said operating mechanism imparts movement to said ticket-issuing device after said controlling mechanism has been actuated. 70
74. A ticket-issuing machine provided with mechanism under control of the operator for controlling the issuance of one or a plurality of tickets, a ticket-issuing mechanism, resilient means for causing said ticket-issuing mechanism to operate, a motor-driven element for storing up energy in said resilient means so that it will be ready to operate at the next cycle of operations of the machine, means for holding said resilient means under tension, and means governed by said controlling mechanism for determining when said issuing mechanism shall act. 75
75. A ticket-issuing machine provided with mechanism under control of the operator for issuing one or a plurality of tickets, resilient means forming part of said ticket-issuing mechanism, a motor driven element for storing up energy in said resilient means, means for automatically locking said mechanism after said resilient means has been placed under tension, and means controlled by the operator for releasing said locking means. 80
76. A ticket-issuing machine provided with mechanism under control of the operator for issuing one or a plurality of tickets, resilient means forming part of said ticket-issuing mechanism, a motor-driven element for storing up energy in said resilient means, means for automatically locking said mechanism after said resilient means has been placed under tension, devices for controlling the degree of movement of said ticket-issuing mechanism, and means controlled by the operator for releasing said mechanism from said locking means and for setting in operation one of said devices. 85
77. A ticket-issuing machine provided with a ticket strip feeding mechanism and with a cutting mechanism for severing said strip, a spring for moving said feeding mechanism forwardly, a motor-driven element for positively storing up energy in said spring and for actuating said cutting mechanism to sever the ticket strip, and a controlling mechanism for determining the number of tickets that are issued at each cycle of operations and for causing said feeding mechanism to operate automatically. 90
- In testimony whereof I have hereunto signed my name in the presence of two subscribing witnesses. 95
